8 Claims. (Cl. 101—23)

My invention relates to an apparatus for applying indications of desired character to film strips.

The practice of applying indications or markings to films is fairly general and is done in a variety of ways. Such indications may be applied by photographic exposure, by chemical action, by stamping or by embossing, but each of these steps involves an operation complete in itself and independent of any other step in the production of the film. In the manufacture of cinematographic films the indications are sometimes applied by suitable exposure devices in combination with the operation of perforating the film.

As distinguished from any of the prior art, the present invention contemplates the application of indications or markings on the film by printing, pressing or embossing, positively, concurrently with the cutting of the film into strips, irrespective of whether the film is perforated or not and also irrespective of the dimensions of the film and the purpose for which it is intended. One of the outstanding advantages of the present invention is that a separate procedure or operation is dispensed with and that no special apparatus is required. The invention also makes it impossible for unmarked films to leave the factory.

For practicing the invention I may, for example, provide a knife or knife part of the cutting mechanism for the film with a preferably spring pressed pressing or embossing device which, during the cutting of the film, will impress or emboss the designation into the margin of the film. If the cutting mechanism compresses rotary shears, one of the cutting blades thereof is advantageously connected with a resiliently mounted ring the periphery of which receives the raised or depressed markings or indications and which may be pressed against the film to be marked.

Several forms of apparatus for practicing the invention are shown in the accompanying drawings in which Fig. 1 is a fragmentary axial section; Fig. 2 is a front elevation of a modified form; Fig. 3 is a rear elevation of the form of Fig. 2; Fig. 4 is a side elevation; Fig. 5 is a section on the line A—B of Fig. 3, and Fig. 6 is a fragmentary view illustrating modification of the invention.

Referring to the form shown in Fig. 1, the lower cutter shaft is denoted 1 and carries a plurality of rotary cutter blades 3 separated from one another by spacers 2. The upper cutter shaft is denoted 12 and carries a ring 10 to which the upper cutter blade 11 is secured. The blades 3

and 12 cooperate in the usual manner to sever strips from the film 4.

Movably connected with the ring 10 is a second ring 6 provided with a flange 5. The latter has embossed, engraved or otherwise formed thereon, the letters, numerals, characters and the like which are to be printed, pressed into or embossed on the film 4. Suitably spaced about the outer periphery of the ring 10 and about the inner periphery of the ring 6 are a plurality of pins 8, the pins being secured in position by screwing, welding or otherwise. The pins carried by the ring 10 are opposite those carried by the ring 6 and between the opposed rings are preferably coil springs 9 having a tendency to force the ring 6 in all directions radially away from the ring 10, so that ring 6 is concentric with the ring 10.

The ring 6 is secured to ring 10 by means of screws 7 passing through washers 7'. The connection between the rings 6 and 10 is such that ring 6 cannot move axially with respect to ring 10 but that it may move radially with respect thereto and for that purpose the screws 7 pass through radially elongated slots 7² in the ring 6.

The outer flange diameter 5 of the ring 6 is at least as great as the diameter of the cutter blade 11 secured to the ring 10. As, during the severing of the film, the blade 11 overlaps the blade 3 only about 1 mm., the flange 5 of ring 6 will overcome the force of the spring 9 adjacent the cutting position and will be pressed against the edge of the film strip. In the rotary movement of the cutter 11 carried by the ring 10, the ring 6 connected with the latter will consequently be entrained eccentrically to shaft 12 and will thus effect a continuing pressure of the letters, numbers or markings of the flange 5 against the film 4, thereby printing, impressing or embossing the film as desired.

In lieu of coil springs 9 I may use flat springs 40 and instead of arranging the springs, whether flat or coiled, as shown in Fig. 1 I may arrange them outside of the rings as shown in Figs. 2 to 5. In these figures the springs 9 are retractile springs and their opposite ends engage studs 13 and 14 secured to the rear surfaces of the rings 10 and 6 respectively.

In the modified form of Figs. 2 to 5 the flange as such is omitted and the letters, numbers or the like 15 are formed on raised parts of the periphery of the ring 6. The upper cutter blade 11 is pressed by an annular coil spring 16 against the ring 6, the spring 16 bearing against a flange 17 carried at the front of the ring 10. The engagement between the lateral face of blade 11 and

the support is controlled by the coiled spring 16 whereby these parts are releasable with respect to one another, insuring the necessary resiliency and "give" of the blade during the cutting operation.

5 The device of my invention for marking the edges of films is usable not only with rotary cutters but also with any type of cutting or shearing mechanism, it being within the purview of my invention to provide the upper or lower cutter with a resiliently mounted bar which carries the letters, numbers or other markings at either or both of its ends.

10 By means of my invention the markings are applied to the film in the same operation in which the film is cut. These markings are applied in regular succession, spaced apart any desired distance irrespective of the dimensions of the film. The marking device is positively moved with the cutters during any adjustment of the latter, as when the cutters are moved back or forth on the shafts 1 and 12 and consequently the danger of marking the film at any place other than the edge thereof is precluded. Moreover, every 15 film passing through the cutting machine will be provided with markings.

20 Referring to Figure 6, 18 is the roll of film and 4 is the strip of film to be cut. 19 is a cutting plate or table, 20 the lower cutter and 21 the upper cutter, the cutter bar of the latter being designated 22. The bar carries the impression member 23 adapted to provide the film strip 4 with the desired designation. In order to cut the 25 piece of film from the strip 4, the cutter bar 22 and cutter knife 21, releasably carried thereby, descend and in doing so impresses the designation 23 on the strip 4 resting on the lower member 20. Of course it will be understood that the 30 position of the member 23 may be reversed, i. e. it may be carried by the lower member 20 instead of by the upper member 21.

35 I claim:

1. In apparatus for the purpose specified, the 40 combination with a rotary film cutter, of a support therefor, a member surrounding said support and having means on its periphery for applying markings to films and a resilient connection between said member and said support.

45 2. In apparatus for cutting and marking tapes, the combination with a cutter blade, of a support therefor, a member carried by the said support and provided with means for producing markings on the tape, said member being disposed short of the cutting edge of said blade and movable on

5 said support in the cutting direction of and relatively to said blade.

3. A device as claimed in claim 2, comprising resilient means for supporting said movable member.

4. In apparatus for cutting and marking tapes, the combination of two rotary cutting devices, a shaft supporting each device, an annular member disposed on one of said shafts and associated with the cutting device thereon, a second annular member surrounding said first annular member and carrying means for producing markings on the tape, springs disposed between the first and second annular members to center the latter with respect to said shaft.

10 5. In apparatus for cutting and marking tapes, a shaft, an annular member supported thereby, a cutter blade surrounding said member, a second annular member about the first member and provided with means for producing markings on the 15 tape, a plurality of springs connecting said two annular members, a spring for said first member to urge said cutting blade towards the said second member.

6. A device as claimed in claim 5, in which the 20 inner diameter of the said first annular member is substantially greater than the outer diameter of the supporting shaft, a recess in said shaft, a key on said shaft, an adjustable bolt secured to said first member to engage the said recess of the 25 shaft, and the first member having a recess to receive said key to lock said shaft and first annular member.

7. In an apparatus of the character described 30 the combination with a cutter blade, of a support therefor in releasable engagement with a lateral face of said blade, a member carried by the said support and provided with means for producing markings, the mark producing means on said member being disposed short of the cutting edge 35 of said blade.

8. In an apparatus of the character described, the combination with a cutter blade, of a support therefor in releasable engagement with a lateral face of said blade, a die carried by the said support and having its operative face disposed short of the cutting edge of said blade and a cutting member disposed opposite the said die and cooperating with the latter to mark a material brought between said die and said cutting member, whereby simultaneous cutting of the material is produced.
